UNITED STATES PATENT OFFICE

157,111

TRAINING SEAT OR CHAIR

Russell L. Wenkstern, Spring Park, Minn., assignor to Moulded Products, Inc., Spring Park, Minn., a corporation of Minnesota

Application December 15, 1948, Serial No. 150,167

Term of patent 14 years

(Cl. D5—5)

To all whom it may concern:

Be it known that I, Russell L. Wenkstern, a citizen of the United States, residing at Spring Park, in the county of Hennepin and State of Minnesota, have invented a new, original, and ornamental Design for a Training Seat or Chair, and of which the following is a description, reference being had to the accompanying drawing, forming part thereof.

Figure 1 is a perspective view of a training seat or chair, showing my new design; and

Figure 2 is a perspective view thereof taken from the rear.

I claim:

The ornamental design for a training seat or chair, as shown.

RUSSELL L. WENKSTERN.
